UNITED STATES PATENT OFFICE.

AUGUST DI LORETO, OF RAVENNA, OHIO.

FRUIT-JAR HOLDER.

Application filed April 5, 1922. Serial No. 549,688.

To all whom it may concern:

Be it known that I, AUGUST DI LORETO, a citizen of the United States, residing at Ravenna, in the county of Portage and State 5 of Ohio, have invented a new and useful Fruit-Jar Holder, of which the following is a specification.

This invention aims to provide novel means for holding a glass fruit jar whilst 10 the cover is being threaded thereon, it being a matter of common knowledge that a fruit jar often breaks during the mounting of the cover, the operator being injured if the jar is held in the hands.

15 It is within the province of the disclosure to improve generally and to enhance the utility of devices of that type to which the invention appertains.

With the above and other objects in view, 20 which will appear as the description proceeds, the invention resides in the combination and arrangement of parts and in the details of construction hereinafter described and claimed, it being understood that, within the 25 scope of what is claimed, changes in the precise embodiment of the invention shown can be made without departing from the spirit of the invention.

In the accompanying drawings:—

30 Figure 1 shows in top plan, a device constructed in accordance with the invention, parts being broken away; Figure 2 is a side elevation; Figure 3 is a front elevation wherein parts are broken away.

35 The device forming the subject matter of this invention includes a bracket comprising a standard 1 having an outwardly projecting fixed jaw 2 and supplied with a foot 3 located below the jaw 2, a clamping screw 4

40 being threaded into the foot 3 and being adapted to cooperate with the fixed jaw 2. At its upper end, the standard 1 is supplied with a transverse head 5. There are openings 6 in the head 5, the openings being elongated longitudinally of the head 5. A feed screw 7 is threaded into the head 5. An operating handle 8 is secured at 9 to the outer end of the feed screw 7.

The numeral 10 denotes an arched or U- 50 shaped yoke 10, the ends of the yoke passing through the slots 6 in the head 5, and terminating in eyes 11, adapted to receive removable securing elements 12, to the end that the yoke may be held detachably on the head 5.

55 The yoke 10 is disposed in a plane approxi-

mately at right angles to the standard 1. The bend of the yoke 10 carries a tubular cushion 14, which may be fashioned out of rubber or any other suitable material.

The numeral 15 marks a movable jaw provided in its ends with slots 18, receiving the side portions of the yoke 10, the movable jaw thus being mounted slidably on the yoke, for movement toward and away from the curved intermediate portion of the yoke. 60 The central portion of the movable jaw 15 is enlarged to form a body 16. A seat 17 is formed in the rear edge of the body 16 and is adapted to receive the forward end of the feed screw 7. In the forward edge of the 65 body 16, a concaved recess 19 is formed. A cushion strip 20 made of rubber or any other desired material is mounted in the recess 19 and is held therein by a securing device 21, such as a screw. Owing to the fact that the 70 movable jaw 15 includes the enlarged body 16, the jaw is not weakened by the formation of the seat 17 and the recess 19.

In practical operation, the bracket is held on the edge of the table or other object, by 80 means of the jaw 2 and the clamping screw 4. The fruit jar which is to be sealed is placed within the contour of the yoke 10, in engagement with the cushion 14. The jaw 15 is advanced through the instrumentality of the feed screw 7 until the jar is clamped between the cushion 14 and the cushion 20 on the jaw 15. Thus, the jar is held mechanically, without danger of breaking and the cover may be mounted on the 85 jar, the operator being in no danger of injury, should the jar break, since the jar is not held in the hands of the operator.

What is claimed is:—

1. In a device of the class described, a 95 standard; means for mounting the standard on a support; an arched yoke; a jaw slidable on the yoke, the yoke terminating in eyes, the standard and the jaw having openings of sufficient size to permit the eyes to pass 100 therethrough; securing devices mounted in the eyes and cooperating with the standard to hold the yoke on the standard; and means carried by the standard for advancing the jaw with respect to the yoke.

2. In a device of the class described, a 105 bracket; means for mounting the bracket on a support; a yoke carried by the bracket; a cushion on the intermediate portion of the yoke; a jaw slidable on the yoke, and en- 110

larged intermediate its ends to form a body, the body having a concaved recess in its forward edge, and being provided in its rear edge with a seat; a screw threaded into the bracket and engaged in the seat; and a cushion mounted in the recess and cooperating with the cushion on the yoke.

In testimony that I claim the foregoing as my own, I have hereto affixed my signature in the presence of two witnesses.

AUGUST DI LORETO.
